Patented Dec. 5, 1922.

UNITED STATES PATENT OFFICE.

JESSE D. CROSSLEY, OF DETROIT, MICHIGAN, ASSIGNOR OF ONE-HALF TO CHARLES F. WHITMAN, OF DETROIT, MICHIGAN.

WORK-FEEDING DEVICE.

Application filed June 3, 1921. Serial No. 474,739.

To all whom it may concern:

Be it known that I, JESSE D. CROSSLEY, a citizen of the United States of America, residing at Detroit, in the county of Wayne 5 and State of Michigan, have invented certain new and useful Improvements in Work-Feeding Devices, of which the following is a specification, reference being had therein to the accompanying drawings.

10 This invention relates to a clutch or feeding device that may be advantageously used for gripping and shifting stock which extends axially of the feeding device, and as an instance of such use I may mention a 15 single or multiple spindle automatic screw machine in which a gripping device automatically engages a piece of stock and intermittently advances the same, so that pieces of the stock may be operated upon or 20 used for various purposes.

In my Patent No. 1,367,589, granted Feb. 8, 1921, there is disclosed a feeding device consisting of two or more parts and this invention aims to provide a more simple feeding 25 device which will be just as positive in its action and may be designed for feeding stock of various cross sectional shapes.

My invention further aims to provide, as a new article of manufacture, a clutch made 30 of a hollow piece of material having inward walls providing gripping members adapted to frictionally engage a member placed axially of the clutch to cause a piece of stock to move with the clutch, unless the piece of 35 stock is otherwise held.

The construction entering into my invention will be hereinafter described and then claimed, and reference will now be had to the drawing, wherein

40 Figure 1 is a longitudinal sectional view of a portion of an automatic machine provided with a clutch or feeding device in accordance with this invention, the feeding device being shown in side elevation;

45 Fig. 2 is an enlarged longitudinal sectional view of the clutch or feeding device;

Fig. 3 is a cross sectional view of the same, and

50 Figs. 4 and 5 are similar views showing in cross section different pieces of stock that may be fed or manipulated by my clutch or feeding device.

The clutch or feeding device is preferably made from a single piece of tubular material, 55 and comprises rigid longitudinally alining

cylindrical end portions 1 and 2 connected by an intermediate longitudinally slotted portion which has portions thereof inward to provide a plurality of circumferentially disposed stock engaging members or jaws 3 60 adapted to frictionally engage a piece of stock 4 and hold the stock for movement with the feeding device, unless the stock is otherwise held, when the jaws or members 3 will slide on the piece of stock and eventually 65 obtain a fresh purchase thereon. The intermediate portion has slits or slots 5 extending longitudinally thereof between the rigid end portions 1 and 2, and the material between the slits 5 is somewhat flattened and bent inwardly, so that the members or jaws 3 will be bowed and present convex faces within the bore of the feeding device. It will therefore be possible to spring the members or jaws 3 outwardly and the device may be temporarily elongated by such 70 action, but the resiliency of the members or jaws is at all times sufficient to cause a frictional engagement of the members or jaws with the piece of stock 4 to permit of the 75 feeding device shifting the piece of stock.

As shown in Fig. 3 there may be a multiplicity of slits or slots 5, so as to provide an intermediate portion which is substantially hexagonal in cross section and the plurality 80 of jaws or members are capable of frictionally engaging a cylindrical piece of stock, as shown in Figs. 2 and 3, or a hexagonal piece of stock, as shown in Fig. 4. In some instances the number and spacing of the longitudinal slots 5 will determine the number 85 of gripping members or jaws and the cross sectional shape of the intermediate portion of the device. This is shown in Fig. 5 where the feeding device has opposed members or 90 jaws adapted for gripping a piece of stock which is rectangular in cross section.

Since the end portions 1 and 2 of the feeding device are rigid, it is possible to clamp or otherwise engage either end portion for 100 bodily shifting the feeding device, and as an instance of the connection for the feeding device, the rigid end portion 2 has an exteriorly screwthreaded nipple 7 and this nipple permits of the clutch or feeding device 105 being used in an automatic machine, a portion of which has been shown in Fig. 1 as an instance of a commercial use for the clutch or feeding device.

The machine includes a bearing 8 for a 110

attaching plate 33 is preferably of single piece construction, as in the form illustrated in Figure 1, and the equalizing devices employed in connection with the form shown in Figures 5 and 6 consists of bars 41 supported by cushioning springs 42 and traversed by wings 43 depending from the table top and having a pivotal or rocking mounting thereon as shown at 44, the intermediate portions of said wings forming runners 45 having a tongue and groove engagement with the bars 41 so as to compensate for the angular relative movement in any direction of the table top and supporting frame and serve to prevent the swinging or prolonged vibratory movement of the table top due to the movement of the surface by which the frame of the structure is supported.

Having thus described the invention, what I claim is:

In a table, a top, means supporting said top for substantially universal movement including legs extending upwardly and inwardly, a pendulum for said top, equalizing supports connected to said top at a distance from the axis thereof and to said legs at a distance above the bases of said legs, and said supports being disposed respectively in planes passing intermediate the terminals of the legs supporting them.

In testimony whereof I affix my signature in presence of two witnesses.

ANTONI BULINSKI.
